UNITED STATES PATENT OFFICE.

GOMER W. PRICE, OF SAN FRANCISCO, CALIFORNIA, ASSIGNOR TO G. W. PRICE PUMP AND ENGINE COMPANY, OF SAN FRANCISCO, CALIFORNIA.

PUMP-SHAFT-CASING COUPLING.

Application filed February 11, 1924. Serial No. 691,993.

To all whom it may concern:

Be it known that I, GOMER W. PRICE, a citizen of the United States, residing in the city and county of San Francisco, and State of California, have invented a new and useful Improvement in a Pump-Shaft-Casing Coupling, of which the following is a specification.

My invention relates to improvements in well pump construction wherein sections of a shaft casing are arranged to be independently subjected to tension and are provided with bearings arranged to give flexibility of the casing relative to a drive shaft enclosed therein.

The primary object of my invention is to provide an improved construction for well pumps.

Another object is to provide an improved means for independently subjecting the several sections of a pump shaft casing to tension whereby an increased tension may be created in each section.

A further object is to provide a construction affording flexibility to the shaft casing relative to the shaft.

A still further object is to provide an improved means for maintaining alignment of the shaft and preventing whipping thereof when in operation.

Another object is to provide an improved construction facilitating the construction and assembling of the pump.

I accomplish these and other objects by means of the device disclosed in the drawings forming a part of the present specification wherein like characters of reference are used to designate similar parts throughout said specification and drawings, and in which:

Fig. 1 and 1^a is a broken side elevation of a pump and casings, parts being broken away and shown in section to disclose the application of my improved construction.

Fig. 2 is a vertical section of a portion of the several casings and their connecting means.

Fig. 3 is an enlarged sectional view of a shaft casing coupling.

Referring to the drawings the numeral 1 is used to designate in general a well pump of the rotary type mounted within a well casing 2 and provided with the usual discharge casing 3 and shaft 4 extending from the pump to the top of the well, said shaft

being provided with the usual pulley 6 whereby the pump may be driven. The shaft 4 is enclosed within a casing 7 as in common practice.

In installations of the character disclosed, much difficulty is encountered in keeping the shaft in true alignment and preventing whipping during operation of the pump. In a former application, Serial No. 471,457, filed May 21, 1921, I disclosed one manner in which these difficulties may be overcome namely by subjecting the discharge casing to tension and the shaft casing to compression whereby the two may be trussed against each other to form a rigid structure. However, in some cases it is found that the construction mentioned is too rigid and must be modified in order to meet peculiar conditions such as wells which have not been drilled perfectly true. Under such conditions a slight flexibility must be afforded to the discharge and shaft casings to permit true alignment of the shaft, and other provision made for preventing the whipping of the shaft when in operation. I accomplish this in the following manner.

The discharge casing 3 is formed from a plurality of sections of a desired length the ends of which are threaded into couplings or flange connections 8 arranged to be connected by means of bolts 9 or other suitable securing means. One of the flange connections upon each discharge casing section is provided with centrally disposed collars 11 connected to the flange by webs 12 preferably formed integral therewith and arranged to receive the shaft casing 7.

The shaft casing 7 is composed of a plurality of sections having threaded ends, each section being slidably engaged by one of the collars 11. Sleeves 13 are threaded onto the adjacent ends of adjacent casings sections, to connect the same, said sleeves being arranged to permit the ends of the adjacent sections to be advanced into contacting relation within the sleeve. The shaft casing sections are so arranged with respect to the discharge casing sections and their connecting flanges that when assembled the sleeves 13 will be immediately above the collars 11 so that by advancing the sleeve slightly farther onto the lower casing section the sleeve will bear against said collar and a further turning of the sleeve will create a tension in the section. In this manner any desired tension may be

- independently created in each of the shaft casing sections, each section being assembled and subjected to tension independently of the other sections.
- 5 Each section of the shaft casing 7 is provided with a plurality of bearings 14 secured therein to receive the shaft 4. The bearings 14 are spaced from the ends of the sections and hence from the collar 11 which 10 together with the webs 12 and the flange 8 forms a spider affording a flexible support for the shaft casing to center the same within the discharge casing. The bearings may be secured in any desired manner but 15 I prefer to accomplish this by forming each bearing block with an annular recess 16 which is filled with soft metal through 20 an aperture 17 in the side of the casing after the bearings have been positioned.
- 20 The lowermost casing sections are connected to the pump and the pump lowered into the well, successive casing sections being connected until the pump has been lowered to the desired depth. As successive 25 sections are added, the sleeves 13 are tightened against the collars 11 to create the desired stress in the casing members, this stress being regulated to allow the casings to be bowed to conform to any irregularities 30 in the well as the pump and casing is lowered thereinto. The bending of the casing is imparted to a lesser degree to the shaft casing by virtue of the rigidly mounted spiders. In this connection, however, it 35 is important to note that no bearing is provided for the shaft immediately adjacent to the spider, but that a plurality of bearings are provided at points spaced a considerable distance from said spider. This arrangement causes most of the bending in 40 the shaft casing to occur at the ends of the sections where no bearing is present, such bending permitting the shaft casing 7 to conform to the discharge casing and the 45 well without imparting a similar displacement of the shaft as the absence of a bearing near the point of bending affords sufficient flexibility of the casing relative to the shaft to prevent any material distortion 50 of the shaft under ordinary circumstances. Thus the bending of the discharge casing to conform to irregularities in the well will cause a more gradual bending of the shaft casing so that a portion of the 55 irregularity of the well is compensated for by displacing the shaft casing relative to the center of the discharge casing along the portion at which the curvature is greatest, which in the case of the discharge casing 60 is at the middle portion of any particular section. As above stated the shaft casing is caused to be bent to the greatest degree at the ends of the sections so that the casing is displaced axially from the shaft at the 65 points of maximum curvature and in this
- way sufficient compensation is made to ordinarily avoid imparting an appreciable curvature to the shaft and in extreme conditions to so reduce the necessary curvature of the shaft as not to materially affect the 70 efficiency of the pump.
- The bending of the casings combined with the stresses created by the sleeves 13 when tightened as above described causes sufficient rigidity to maintain the shaft in 75 alignment and effectually prevents whipping of the shaft when the pump is in operation. The several parts are readily assembled in their proper relation as the casing members are made in standard lengths 80 such as will bring the spiders and sleeves in the desired relation so that only a slight turning of each sleeve 13 will independently create the desired stresses in the corresponding casing sections. 85
- Having thus described my invention what I claim as new and desire to secure by Letters Patent is:
1. In a well pump, the combination with a drive shaft, of a casing formed from a plurality of sections; sleeves connecting the ends of adjacent sections; and means engaging said sleeves when said sleeves are tightened onto one of the said adjacent sections whereby said section may be subjected to tension independently of the other sections. 90
  2. In a well pump; the combination with a drive shaft, of a shaft casing formed from a plurality of sections; sleeves connecting the ends of adjacent sections; and spiders rigidly mounted adjacent the sleeves to be engaged thereby whereby said sleeves may be tightened thereagainst to subject each of the sections to tension. 100
  3. In a well pump, the combination with a drive shaft, of a shaft casing formed from a plurality of sections having threaded ends; sleeves engaging said threaded ends to connect adjacent sections; a spider rigidly mounted adjacent each sleeve; a collar formed upon said spider to slidably engage the shaft casing, said collar being arranged to be engaged by the sleeve adjacent thereto whereby each sleeve may be tightened to subject the corresponding casing section to tension. 110
  4. In a well pump, the combination with a drive shaft, of a shaft casing enclosing said drive shaft, said casing being formed from a plurality of sections; spiders rigidly mounted adjacent the ends of the sections; means connecting the ends of the sections arranged to be tightened against the spiders for subjecting the sections to tension; and a plurality of bearings mounted within each section to receive the shaft, said bearings being spaced away from the points engaged by the rigid spiders to give flexibility of the casing relative to the shaft. 120

5. In a well pump, the combination with a drive shaft and discharge casing formed from a plurality of sections, of flanges connecting the ends of sections forming said discharge casing; a spider formed integral with one of the flanges upon each section; a shaft casing formed from a plurality of sections to enclose the shaft; sleeves connecting adjacent ends of the shaft casing sections, each sleeve being arranged to engage one of the spiders to subject one of the shaft casing sections to tension, 20
5 each sleeve being arranged to engage one of the spiders to subject one of the shaft casing sections to tension; a spider formed integral with one of the flanges upon each section; a shaft casing formed from a plurality of sections to enclose the shaft; sleeves connecting adjacent ends of the shaft casing sections, 25
10 each sleeve being arranged to engage one of the spiders to subject one of the shaft casing sections to tension.
6. In a well pump, the combination with a drive shaft and discharge casing formed from a plurality of sections, of flanges connecting the ends of sections forming said

discharge casing; a spider formed integral with one of the flanges upon each section; a shaft casing formed from a plurality of sections to enclose the shaft; sleeves connecting adjacent ends of the shaft casing sections, each sleeve being arranged to engage one of the spiders to subject one of the shaft casing sections to tension; and a plurality of shaft bearings mounted within each casing section, said bearing being spaced away from the spiders to give flexibility of the casing relative to the shaft.

In witness whereof I hereunto set my signature.

GOMER W. PRICE.
